UNITED STATES PATENT OFFICE.

THOMAS WATTS, OF VANCOUVER, CANADA, ASSIGNOR TO THOMAS HERBERT WYMONDE, LATE OF LONDON, ENGLAND.

FISH-OFFAL DIGESTER.

SPECIFICATION forming part of Letters Patent No. 651,585, dated June 12, 1900.

Application filed July 18, 1898. Serial No. 686,287. (No model.)

To all whom it may concern:

Be it known that I, THOMAS WATTS, a citizen of the Dominion of Canada, residing at Vancouver, in the Province of British Columbia, Canada, have invented a new and useful Improvement in Fish-Offal Digesters, of which the following is a specification.

This invention has for its purpose to provide a cheap, simple, and easily-manipulated means for extracting the oil and gelatin from fish-offal while in the digesters preparatory to being converted into guano or plant-food; and it consists in certain details of construction and combination of parts hereinafter described, and pointed out in the claims.

I attain the above object by the mechanism illustrated in the accompanying drawings, in which—

Figure 1 is a vertical section of my improvement, showing the same applied to a conveyer mechanism hereinafter described. Fig. 2 is an enlarged transverse sectional plan of the digester, taken on line *b b* in Fig. 1. Fig. 3 is a detail view of one of the movable baffles.

Similar numerals refer to similar parts throughout the several views, in which—

10 indicates a conveyer-chute arranged over inclined hopper tanks or chutes 11. The offal is conveyed along the chute 10 by an endless 30 device which is common to conveyers of this class, and in the chute 10 over each tank is a drop-door 12. These doors 12 are arranged over the centers of each tank and are provided with means of opening or closing them at pleasure. The bottoms of the tanks are sloping forward, as 13, and their forward sides are contracted into chutes 14. Each chute 14 is provided with a trap-door 14^a, designed to rise and fall vertically by means of a rack 15, operated by a pinion 16, which is fixed to a wheel-shaft 17.

The tanks 11 are so elevated that the matters deposited therein through the drop-doors 12 will pass to the chutes 14 by gravity. Pivotally secured to the projecting lips of the chutes 14 are movable ducts 18. These ducts when depressed communicate with openings 19 in the upper ends of vertically-placed digesters 20, and when the chutes are elevated, as shown by dotted lines in Fig. 1, the

openings 19 are sealed by detachable doors or by any other means that is found convenient.

As clearly shown in Figs. 1 and 2, each digester 20 is provided at some distance from its conoidal bottom with a sloping foraminous bottom 21, and this is borne by an annular support 22, secured to the inner periphery of the digester, and by cross-bars 23, supported by the same.

At the lower sides of the sloping bottom 21 is an opening 24 in the shell of the digester. This opening 24 is provided with means for making it steam-tight for a purpose to appear later.

At the top of each digester are arranged a steam-pipe 25, a pressure-gage pipe 26, and a safety-valve vent 27. The two latter provide against too great a strain being exercised within the digesters.

At the lower depending ends of the digesters are arranged inlet-pipes 28. These pipes pass through the shells of the depending conoidal ends of the digesters beneath the perforated bottoms 21 therein, and their inner ends curve upward and are provided with baffles 29, which are designed to slip up and down on upwardly-projecting pins over the mouths of the pipes 28. These baffles 29 provide for the steam being evenly distributed under the bottoms of the perforated grids 21, and when the pressure is brought to bear from above, as will be understood presently, the baffles will lie over the mouths of the pipes and prevent any matters passing therein.

At the lower point of the depending ends of the digesters are pipes 30. These pipes are for the purpose of drawing off oil and moisture from the offal that is being treated, which moisture will be in the form of oil, gelatin, and water.

The digesters are suitably supported in a frame A and the hopper-tanks are arranged at a suitable distance above the same, so that the offal in such tanks will pass to the digesters by gravity through the trap-door 14^a when such door is opened, as described above.

In the operation of my invention the offal is brought along the chute 10 by conveyers and is dropped through the drop-door 12 into the tanks 11. When it is desirous to use but

one tank and digester, the doors 12 are all closed except the one in use. It is thus shown that one or as many of the tanks as desired may be used at the same time to suit the requirements for disposing of the offal. By raising the trap-door 14^a the offal passes into the digesters until they are as full as desired, when the trap-doors are closed and the openings 19 in the digesters are also closed tight, so that there can be little or no escape of steam. Steam is then turned on by the pipes 25 and 28 until the entire mass has been permeated and cooked, which usually occupies forty-five to sixty minutes, according to the steam-pressure. When the cooking process has been completed, the pressure is shut off from the port 28 and extra pressure is increased through the port 25. This will drive all moisture downward through the mass and through the bottom 21, from where it is driven off through the pipe 30 into condensing tanks to cool, when the oil will be released from the gelatin and water and may be drawn off into tanks arranged for its reception. After this the water is evaporated from the gelatin by heat, and the oil and the gelatin may then be refined and placed in convenient marketable form. After all moisture has been ejected from the mass in the digesters, as before mentioned, the doors 24 are opened and the residue is then taken from the digesters, when they will be ready for another charge. The residue is stored away to be further treated for making plant food or guano.

Having thus described my invention and the operation thereof, what I claim, and desire to secure by Letters Patent, is—

1. In an apparatus of the class specified, the combination with a vessel having a discharge-door; of an inclined, foraminous plate located in said digester and having its delivery end located opposite said discharge-door;

two steam-pipes connected with said digester and passing into the same, and the outlets thereof being located respectively above and below said foraminous plate; and a steam-pressure-operated device located to close one of said steam-pipes, substantially as specified.

2. In an apparatus of the class specified, the combination with a closed vessel having conoidal ends, and having an opening in the upper end of the same; of a foraminous plate supported at an inclination above the lower end; a closable door on said vessel, disposed above said plate; pipes for supplying steam above and below said foraminous plate; and a baffle carried by one of the pipes, and closable by steam-pressure from the other pipe, substantially as specified.

3. In an apparatus of the class specified, the combination with a vessel having an inferior foraminous plate, and also having a discharge-pipe located at the lower end of the vessel; of a discharge-controlling door covering an opening in the tank above the delivery end of said foraminous plate; two steam-pipes leading into the vessel, and their outlets being located respectively above and below said plate; and a baffle carried by the one steam-pipe and operated by steam-pressure from the other pipe, substantially as specified.

4. In an apparatus for the purpose described, the combination of a cylindrical digester having conoidal ends and provided between the same with a discharge-opening, a perforated bottom, a safety-vent 27 at the upper apex of the digester, and a discharge-pipe at the lower apex of the same, substantially as described.

THOMAS WATTS.
